UNITED STATES PATENT OFFICE.

JAMES GAYLEY, OF BRADDOCK, PENNSYLVANIA.

BOSH-PLATE FOR FURNACES.

SPECIFICATION forming part of Letters Patent No. 463,663, dated November 24, 1891.

Application filed May 4, 1891. Serial No. 391,552. (No model.)

To all whom it may concern:

Be it known that I, JAMES GAYLEY, of Brad-
dock, in the county of Allegheny and State of
Pennsylvania, have invented a new and use-
ful Improvement in Bosh-Plates for Furnaces,
of which the following is a full, clear, and ex-
act description, reference being had to the
accompanying drawings, forming part of this
specification, in which—

10 Figure 1 is a side elevation, partly in ver-
tical section, showing a blast-furnace provided
with my improved bosh-plates. Fig. 2 is a
horizontal sectional view of a single bosh-
plate on the line II II of Fig. 5. Fig. 3 is a
15 section on the line III III of Fig. 2. Fig. 4 is
an end view, and Fig. 5 a front view, respect-
ively, of the bosh-plate of Fig. 2.

In the bosh-plate now commonly in use two
small separate water-courses are employed,
20 and when the inner course is injured it is
customary to close the water communication
and allow it to burn off, using only the outer
course. This involves a great loss of metal,
and consequently as these plates are made of
25 bronze a considerable expense.

In my improved construction these difficul-
ties are obviated and a bosh-plate is employed
which contains a single water-course of large
30 capacity and of such shape that the walls
may be easily repaired. Moreover, no spe-
cial bricks are required in building the plates
into the furnace-walls, and the shape and con-
tinuity of the walls may remain unaltered.

In the drawings, 2 represents the wall of
35 the furnace, and 33 the bosh-plates arranged,
preferably, in several horizontal series around
the furnace-bosh. Each bosh-plate is made
tapering in width and thickness, as shown
in Figs. 2 and 3, producing a wedge-shaped
40 plate, and is provided at its inner side with a
water-chamber 4, having the inlet-pipe 5 and
exit-pipe 6. Between these pipes is an air-
chamber 7, open at its outer side and having
supporting-ribs 8, which form chambers com-
45 municating with each other by apertures 9.
If desired, studs may be used in place of the
partitions; but I prefer the construction shown.
This chamber does not extend to the outer

ends of the pipes 5 and 6; but an offset 10 is
provided, in which loose bricks may be in- 50
serted to preserve the continuity of the walls,
leaving only the pipes 5 and 6 protruding
therefrom. In Fig. 1 the series 11 is shown
without the filling-bricks, while series 12 illus-
trates the bricks in place. 55

It will be seen from Figs. 2 and 3 that no
baffle-plates or partitions are employed in the
chamber 4, the top plate being supported by
a series of small studs or posts 13. This con-
stitutes an important item of my invention, 60
since deposits constantly form on the baffles
commonly used, clogging up the passages and
preventing the flow of the cooling-fluid. In
building the plates into the furnace-wall the
65 top surface is preferably made horizontal, the
entire taper coming on the bottom of the
plate, on account of ease in construction, the
use of special forms of bricks being thus
avoided.

A practical test of these plates has shown 70
that they possess remarkable cooling power
and stability in resisting pressure, while the
condition of each plate is easily ascertained
by inspection of the air-chamber 7 and any
leak easily located and repaired. 75

What I claim is—

1. A cooling-plate having a plane-surfaced
inclined top and bottom and openings for a
cooling medium, substantially as described.

2. A cooling-plate containing a single closed 80
and unobstructed water-chamber, pipes of
smaller diameter leading thereto, and vertical
studs in the water-chamber, substantially as
and for the purposes described.

3. A bosh-plate having an inner water-cham- 85
ber, a pipe extending from each end of said
chamber, and an air-chamber between and
shorter than said pipes, producing an offset
between the pipes, substantially as and for the
purposes described. 90

In testimony whereof I have hereunto set
my hand this 2d day of May, A. D. 1891.

JAMES GAYLEY.
